UNITED STATES PATENT OFFICE.

AURIN WOOD, OF WORCESTER, ASSIGNOR TO GEORGE DRAPER & SONS, OF HOPEDALE, MASSACHUSETTS.

SPINDLE-BEARING.

SPECIFICATION forming part of Letters Patent No. 538,995, dated May 7, 1895.

Application filed July 30, 1894. Serial No. 519,022. (No model.)

To all whom it may concern:

Be it known that I, AURIN WOOD, of Worcester, county of Worcester, State of Massachusetts, have invented an Improvement in Spindle-Bearings, of which the following description, in connection with the accompanying drawings, is a specification, like letters and numerals on the drawings representing like parts.

- 10 This invention has for its object to improve spindle bearings as to the means for preserving the proper fit between the tapered exterior of the pintle of the spindle and the tapered interior of the lateral bearing. To effect this adjustment the construction of the parts must be such as to enable the distance between the step and that part of the lateral bearing which surrounds the pintle just above the step to be changed or made more or less, 15 or, in other words, the lateral bearing and step must be separable and be capable of having their positions changed relatively one to the other. This can be done by either raising or lowering the lateral bearing, or the step.
- 20 In my invention the adjusting device is located in and accessible from outside the oiling leg.

Figure 1, in vertical section, shows a spindle in a bearing containing my invention in one practical form; Fig. 2, a top or plan view of the parts shown in Fig. 1, the section of Fig. 1 being in the line x , Fig. 2. Fig. 3 is a section below the line x' , Fig. 1. Fig. 4 is a vertical section showing a modification of my invention; Fig. 5, a section in the line x'' , Fig. 4; Fig. 6, an outside view of the bolster. Fig. 7 shows the lateral bearing in longitudinal section, and Fig. 8 a section in the line x'' , Fig. 5.

- 40 The rail A, on which is the supporting case B, is secured by nut C, and the sleeve whirl spindle D having a tapered pintle, are all as usual. The supporting case has an inclined oiling leg or branch b, through which is passed the oil to oil the spindle and its bearings composed of a lateral bearing c, tapered internally, and a step d. I have provided the bearing c externally with a suitable notch or shoulder c', and I have inserted in the hollow 45 leg or branch an adjusting device e, shown as

a hollow shaft having a shoulder at 2 to rest against a shoulder of the branch, the inner end of said adjusting device having an eccentric projection e' to enter the notch c' of the bearing c, so that the partial rotation of 55 said adjusting device by a screw-driver or other proper tool engaging the notch e' thereof, enables the position of the bearing c to be changed relatively to the step to provide for the proper fit between the exterior of the pintle and the interior of the bearing, a suitable set screw f serving to hold the adjusting device in adjusted position.

In my invention it will be seen that the adjustment provided for may be effected readily 65 while the spindle is running as well as while at rest, and without the loss of oil.

In the modification of my invention Figs. 4 to 8, I have provided for moving the step rather than the lateral bearing, one being the 70 equivalent of the other in result, and therefore an equivalent. Referring to said modification, the lateral bearing g is prolonged, and its lower end is so fixed with relation to the outside supporting case that it cannot rise 75 therein when effecting the relative adjustment of the parts to secure the proper fit between the externally tapered pintle and the tapered interior of the said bearing, the connection being shown as effected by a screw- 80 thread at g². The bearing g is grooved externally for part of its length to receive the shank h of the step h', the latter being extended into the bearing and across the pintle chamber in a slot h². The shank h is notched 85 at h³ to be engaged by a suitable projection h⁴ on the adjusting device h⁵, placed in the oiling leg or branch m, the rotation of said adjusting device with its projection or projections h⁴ in engagement with the projections 90 h³ moving the step to the extent desired to make the proper fit between the pintle and lateral bearing.

In my invention the adjusting device for changing the relative positions of the lateral 95 bearing and step to insure the proper fit or looseness between the tapered pintle and step, is located above the top of the spindle-rail and it is shown as accessible through the oiling leg, and while I have shown two forms of 100

adjusting devices, yet this invention is not limited to the exact shape shown for said devices.

Having described my invention, what I claim as new, and desire to secure by Letters Patent, is—

1. A supporting case having an oiling leg or branch, a spindle having a pintle tapered externally, two members, consisting of a lateral bearing tapered internally, and a step, combined with adjusting mechanism for said bearing and step, located in said leg or branch, in positive engagement with one of said members to move it relatively to the other, whereby the relative position of the said lateral bearing and step may be positively changed when desired, for the purposes set forth.
- 15

2. The supporting case having an oiling leg or branch, and a lateral bearing and step located in said supporting case, combined with an adjusting device located in said leg or branch, said adjusting device having through it an oil passage and provided at its inner end with a projection, whereby by the rotation of said adjusting device the relative positions of the bearing and step may be changed in the supporting case, substantially as described.

In testimony whereof I have signed my name to this specification in the presence of two subscribing witnesses.

AURIN WOOD.
